UNITED STATES PATENT OFFICE.

JAMES B. BLAIR, OF DECATUR, ILLINOIS, ASSIGNOR OF ONE-HALF TO FRANK B. OWENS, OF DECATUR, ILLINOIS.

DESIGN FOR A TRAIL-MARKER.

55,022.

Specification for Design.

Patented May 4, 1920.

Application filed September 15, 1919. Serial No. 324,029. Term of patent 7 years.

To all whom it may concern:

Be it known that I, JAMES B. BLAIR, a citizen of the United States, residing at Decatur, in the county of Macon and State of Illinois, have invented a new, original, and ornamental Design for a Trail-Marker, of which the following is a specification, reference being had to the accompanying drawing, forming a part thereof.

The figure is an elevation of a trail marker, showing my new design.

I claim:

The ornamental design for a trail marker, as shown.

JAMES B. BLAIR.
